UNITED STATES PATENT OFFICE.

JOHN F. EAST, OF NORFOLK, VIRGINIA.

BARREL-COVER.

No. 872,614.

Specification of Letters Patent.

Patented Dec. 3, 1907.

Application filed August 17, 1906. Serial No. 331,052.

To all whom it may concern:

Be it known that I, JOHN F. EAST, a citizen of the United States, residing at Norfolk, in the county of Norfolk and State of Virginia, have invented certain new and useful improvements in Barrel-Covers, of which the following is a specification, reference being had therein to the accompanying drawing.

This invention relates to improvements in 10 barrel covers, and particularly to a flexible wood-fiber cover.

The object of the invention is the construction of a cover adapted to conform to the contour or shape of the contents of a barrel 15 when in a heaped-up condition.

Another object of the invention is the construction of a flexible, ventilated wood-fiber cover.

A further object of the invention is the 20 construction of a ventilated cover which will conform to the contour of the contents of a barrel when in a heaped-up condition, and which cover can be quickly secured to or removed from the barrel.

25 With these and other objects in view, the invention consists of certain novel constructions, combinations, and arrangements of parts, as will be hereinafter fully described and claimed.

30 In the drawings: Figure 1 is a top plan view of my improved cover. Fig. 2 is an inverted plan view of the cover depicted in Fig. 1. Fig. 3 is a perspective view of my cover showing the same applied to a barrel 35 containing produce in a heaped-up condition.

Prior to my invention, in the shipment of 40 vegetables, such as kale, spinach, and cabbage, and in fact, many kinds of fruits, barrels provided with burlap covers were employed. The purpose of the burlap cover was for ventilation and accessibility to examine the contents of said barrel. These burlap covers were usually made from waste 45 material, and were unsanitary. To minimize the cost of the covers, and, overcome any objectionable feature thereto, I have invented the hereinafter specifically described wood-fiber cover.

50 In the drawings, 1 and 2 designate parallel,

outer, wood-fiber strips, which are positioned at right-angles to parallel strips 3 and 4. Intermediate strips 5 and 6 are interwoven between said strips 1, 2, 3, and 4. It will be obvious, upon referring to the drawings, that 55 all of the strips of the cover are interwoven. The outer strips 1, 2, 3, and 4 are secured together, by suitable fastening means, as for instance, staples 7.

The flexible, interwoven structure is reinforced for producing a highly efficient device, and for this reason, I employ reinforcing members, preferably wires, 8 and 9. These reinforcing members or wires are, of necessity, of sufficient resiliency to accommodate the different shapes assumed by the cover. The reinforcing wires are crossed, as at 10', and are interwoven among the strips of the cover. The wires are straddled by the staples or fastening means 7. The 70 ends 10 of said wires are bent over, Fig. 2, and are positioned substantially parallel with the strips of the head and the body portion of said wires. The bending of the ends of these reinforcing members or wires not 75 only places the ends out of the way, but also insures no sliding movement, thereby preventing said reinforcing members being displaced off of said strips; furthermore, the members 8 and 9 secure the strips of the 80 head together until the staples 7 are forced through said strips.

It will be obvious that I do not limit myself to wires as the reinforcing means for the wood-fiber cover, because I have described 85 the same as "reinforcing members", which contemplates employing other kinds of metal reinforcing means, in the construction of the cover, as for instance, ordinary metallic strips of sheet-metal, or the like.

90 My flexible cover or head is usually attached to the barrel 11 (of any preferred structure) after said barrel has been filled with the produce to be shipped, by placing a hoop or ring 12 over said head or cover, 95 and forcing the hoop down upon the sides of the barrel. While it is unnecessary to heap-up the contents of the barrel, the flexibility of the cover will permit the same to be accommodated to such conditions. It will be ob- 100

vious that by reason of securing the cover to the barrel by hoop 12, the same can be quickly attached or detached as desired.

The strips employed in constructing the cover are of very thin wood-fiber, whereby a head of substantially the flexibility of burlap or similar cloth is produced. By reinforcing the flexible cover, the same is doubly strengthened. It will also be noted that all of the ends of the wood strips employed in constructing the cover are left free.

From the foregoing description, and upon reference to the accompanying drawing, it is to be understood that the outer strips are positioned at right-angles to each other, and that the staples extend through the engaging, crossed portions of the outer strips; owing to the two-part structure of the staples, a rigid fastening-means is obtained for holding the entire cover together, which will prevent any independent, pivotal movement or sagging of the outer strips of the cover, which would likely be the case if an ordinary tack or single-piece fastening means was employed instead of the staples. The intermediate interwoven strips are retained in their assembled position upon the outer strips, without being held by any fastening means. By reason of the interwoven structure of the fastening means 7, under normal conditions, the cover is retained at all times in its assembled, circular shape. The fastening of the outer strips together forms a substantially square frame, between which the unfastened interwoven strips 5 and 6 are positioned.

What I claim is:

1. A flat, flexible wood-fiber barrel cover, comprising flat, crossed strips having their ends free, a straight reinforcing member extending across said strips and provided with hooked ends, the outer strips positioned at right-angles to each other, and each of said hooked ends positioned over the outer edges of a plurality of outer, angularly-disposed strips and upon opposite sides of said strips for preventing displacement of said reinforcing member off of said strips and securing said strips together.

50 2. A flat wood-fiber barrel cover, comprising interwoven, crossed, flexible strips having their ends free, crossed reinforcing members interwoven between said strips and extending across the engaging-portions of the outer strips intermediate the ends of said strips, and staples straddling said wires and extending through the engaging-portions of the outer strips, thereby rigidly securing said wires and outer strips together.

60 3. A flat, flexible, wood-fiber barrel cover, comprising interwoven strips having their outer ends free, and reinforcing members interwoven with said strips and having each of

their outer ends bent around the outer edges of a plurality of the outer strips for securing all of the strips together.

4. A flat, flexible wood-fiber barrel cover, comprising interwoven strips having their outer ends free, and reinforcing means extending entirely across the interwoven portion of said strips and surrounding the outer edges of the outer strips and positioned upon opposite sides of said strips for securing all of the strips together.

5. A flat wood-fiber barrel cover, comprising interwoven flexible strips having their ends free, the outer strips disposed at right-angles to each other, each outer strip extending across a plurality of the angularly-disposed, outer strips intermediate their ends, and staples extending through the engaging-portions of the angularly-disposed outer strips, thereby rigidly securing said outer strips together and preventing independent movement of said outer strips with respect to each other.

6. A flat, circular wood-fiber barrel cover, comprising interwoven, crossed strips having their ends free, and reinforcing means extending across the engaging portions of said strips and positioned intermediate the ends of said strips and extending over a plurality of the side-edges of the outer strips for preventing displacement of said reinforcing means and securing said strips together.

7. As a new article of manufacture, a flat, flexible wood-fiber barrel cover, comprising interwoven outer and intermediate strips having their ends free, each outer strip extending across a plurality of outer strips intermediate their ends, and double fastening means extending through each of the engaging and crossing portions of the outer strips for rigidly securing all of the outer strips together, and thereby securing the intermediate strips together upon said outer strips.

8. As a new article of manufacture, a flat wood-fiber barrel cover, comprising interwoven, flexible strips having their ends free, each of the outer strips crossing a plurality of outer strips intermediate their ends, and fastening means extending through the engaging and crossing portions of the outer strips for fixedly securing all of the strips together.

9. A flat wood-fiber barrel cover, comprising flexible, interwoven strips having their ends free, the outer strips crossing intermediate their ends, reinforcing means extending across all of and of less length than said strips, said reinforcing means positioned around the edges of a plurality of outer strips and upon opposite sides of a plurality of crossed portions of the outer strips.

10. As a new article of manufacture, a flat, flexible wood-fiber barrel cover, comprising interwoven strips having their ends free,

and fastening means extending transversely through the crossed portions of some of the strips for securing all of the strips together.

11. As a new article of manufacture, a flat flexible wood-fiber barrel cover, comprising interwoven strips having their ends free, and reinforcing means extending entirely across all of and of less length than said strips, and said reinforcing means positioned around the

edges of the outer strips and upon opposite 10 sides of the engaging and crossing portions of the outer strips.

In testimony whereof I hereunto affix my signature in presence of two witnesses.

JOHN F. EAST.
